TWIN COMPARTMENT ANIMAL FEEDING BOWL

Marvin A. Goldman, Great Neck, and Jerome N. Goldman, New York, N.Y., assignors to Penn Plax Plastics, Inc., Jamaica, N.Y.

Filed Jan. 6, 1972, Ser. No. 215,989

Term of patent 14 years

Int. Cl. D30—03

U.S. Cl. D30—16

FIG. 1

FIG. 2

FIG. 3

FIG. 4

FIG. 5

FIG. 6

FIG. 1 is a perspective view of a twin compartment animal feeding bowl, showing our new design;

FIG. 2 is a top plan view;

FIG. 3 is a front elevational view, the rear being substantially a mirror image thereof;

FIG. 4 is a side elevational view, the opposite side being substantially a mirror image thereof;

FIG. 5 is a bottom plan view; and

FIG. 6 is a cross-sectional view thereof taken on line 6—6 in FIG. 2.

We claim:

The ornamental design for a twin compartment animal feeding bowl, substantially as shown and described.
